ROBERT BOLLING, OF DETROIT, MICHIGAN

BAKE OVEN

Application filed December 19, 1930. Serial No. 503,455.

This invention relates to a bake oven and has to do especially with a rotary oven wherein the articles which are heat treated or baked are moved through the heat chamber. The object of the invention is the provision of an improved bake oven structure, and in this regard there are several novel features which taken singly, or in combination serve to provide an oven of improved operation. These 10 points of novelty will be brought out in the detailed description.

Fig. 1 is a front elevational view of an oven constructed in accordance with the invention.

15 Fig. 2 is a top plan view thereof.

Fig. 3 is a vertical section taken on line 3—3 of Fig. 4.

Fig. 4 is a horizontal section taken substantially on line 4—4 of Fig. 3.

20 Fig. 5 is a detailed perspective showing the heating unit and the interior of the oven.

The oven consists of a wall structure, and this wall structure may be of multi-sided arrangement. This is illustrated in Figs. 2 and 25 4 wherein the particular oven shown is of octagonal shape. A greater or less number of sides may be provided. The outer wall shown generally at 1 is made up of members which may be in the form of sheet metal plates 30 2 bent intermediate their length to form the corners 3. Adjacent plates are joined preferably on a flat side of the oven, as illustrated at 4; this joint may comprise a T iron which may be constructed by two angle irons placed 35 back to back with the oppositely extending plates suitably united or secured to the T iron. These plates or sections may be suitably finished as by means of porcelain or the like. As shown in Fig. 1 there may be a central reinforcing band 5. There may be an inner wall similar to the outer wall composed of sections 6 shaped to correspond to the shape of the outer wall and joined at their ends as at 7. The inner and outer walls may be spaced 45 apart for insulation purposes, and a suitable insulation material such as asbestos substance 8 may be disposed between the walls. At the bottom of the furnace the space between the walls is closed as at 9 while the interior of the 50 oven is preferably provided with a bottom or

floor 10 with an outer bottom or floor 11 between which there may be a suitable insulation 12. The top of the oven may be double having an outer top 13 and an inner top 14 with insulation 15 between them. The insulation 8, 12 55 and 15 may comprise substantially one surrounding body of insulation material.

As shown in Fig. 5 the heat unit is shown as having a fire box 20, a top 21. The oven is provided with a suitable door 22 in alignment with the fire box. The fuel may be gas or any suitable combustible material of solid formation, and there may be a draft door 23 in the oven wall in substantial alignment with a compartment 24 in the heating unit. Where 60 solid fuel is used the ashes or the like may be removed through this door.

The goods to be baked may be disposed on shelves in the oven and preferably there are a plurality of such shelves. In the present instance there are two. These shelves are preferably rotatable, and for this purpose there is a central shaft 25. The upper shelf is shown at 26, while the lower shelf is at 27, both carried by the shaft to be rotated thereby. Suitable means such as an electric motor 28 through reduction gears 29 may rotate the shaft during the baking operation. For the purpose of loading and unloading the shaft may be rotated by means 70 of the hand wheel 30 and the connections shown.

The central shaft may be insulated from heat in its lower portion as illustrated at 31. The heated currents may be directed in 85 such manner as to flow across the goods being baked. In this regard the lower shelf 27 may be provided with a central opening through which the heated currents pass as illustrated by the arrows. In this central 90 opening may be positioned a pipe-like member 32 having at its upper end an outwardly extending flange or deflector 33. It will be noted that the heated currents accordingly pass through the member 32 and by reason 95 of deflector 33 the heated currents are brought up close to the under side of the upper shelf 26. This shelf is closed or substantially closed in its central portion, but its edges are removed from the inner walls 100

of the oven so that the heated currents may then pass radially outward, then up around the upper edges 26 as illustrated by the arrows. Inasmuch as the heat unit is located 5 in the bottom of the oven this invention provides for more or less heat control as between the shelves 26 and 27. In other words, where it is desirable, although one shelf is closer to the heat unit than the other, 10 substantially the same heat may be communicated to both; on the other hand, a predetermined controlled relation may be provided wherein one shelf is a little hotter than the other. Accordingly, the deflector 15 brings the heated currents close to the underside of the upper shelf; the lower shelf may be protected by a partition 34 positioned below the shelf 27. This partition may be raised or lowered as desired varying the space between it and the lower shelf 27. Accordingly, with this partition and with the deflector the arrangement of the 20 parts may be such that a substantially uniform heating action is obtained both in the upper and lower shelves. The partition 34 25 protects the lower shelf from the intense heat in close proximity thereto while the heated gases are directed up to the upper shelf. The partition 34 and the shelves may be of suitable refractory material. The partition 34 has a central opening 35 which may be in alignment with the member 32.

The heated products of combustion may 30 pass out of the fire chamber through openings 40 into the lower compartment below the partition 34 and then into flues 41 in the wall of the oven. Whereas the fire box 35 may be at the forward side of the oven the flues may be at the rear side, as best illustrated in Fig. 4. These flues may extend upwardly in the wall of the oven and direct the products of combustion into an upper compartment 42 cut off from the compartment containing the shelves and bake 40 goods by a floor 43, and in the compartment 42 the central shaft may be insulated as at 48. The flues 41 may open into the rear part 45 of the compartment 42 while the smoke pipe may be at the front, as illustrated at 44. Thus the products of combustion traverse 50 the lower end of the oven from front to rear, pass upwardly into the top of the oven and then again traverse the oven from rear to front, then out the smoke stack. This affords an efficient oven from the standpoint 55 of utilizing available heat. There may be deposits of soot or the like upon the floor 43, and a suitable door 45 may be located in the oven wall in alignment with the compartment 42 by means of which the same 60 may be removed. The shelves may be loaded and unloaded through the means of doors 46 and 47. A single door may be used if desired instead of two doors.

65 I claim:

1. In a bake oven, walls defining an enclosure, a plurality of vertically spaced shelves for supporting bake goods, a heat unit in the lower part of the enclosure, the lower shelf being provided with a substantially centrally disposed opening, the upper shelf being substantially closed centrally but spaced from the walls at its edges, and a deflector associated with the lower shelf for directing heated currents which pass through the opening in the lower shelf into close proximity with the upper shelf. 70

2. In a bake oven, the combination of walls defining an enclosure, a heat unit in the lower part of the enclosure, a plurality of vertically spaced shelves for supporting bake goods alternately opened and closed near their central portion, and a deflector member positioned to direct heated currents which pass through the central opening of one shelf in close proximity to the upper shelf. 75

3. In a bake oven, walls defining an oven enclosure, a lower rotary shelf, an upper rotary shelf, a central opening in the lower shelf, a tubular like member associated with said opening for directing heated currents which pass through said opening into close proximity to the upper shelf. 80

4. In a bake oven, walls defining an oven enclosure, a heat unit in the lower portion of the enclosure, a lower rotary shelf having a central opening for the passage of heated currents therethrough, an upper rotary shelf, and a tubular like member positioned in association with the opening in the lower shelf for directing heated currents substantially against the under side of the upper shelf. 90

5. In a bake oven, walls defining an oven enclosure, a heat unit in the lower portion of the enclosure, a lower rotary shelf having a central opening for the passage of heated currents therethrough, an upper rotary shelf, and a tubular like member positioned in association with the opening in the lower shelf for directing heated currents substantially against the under side of the upper shelf, said upper shelf being substantially closed in its central zone with its outer edges spaced from said walls. 100

6. In a bake oven, walls defining an oven enclosure, a heat unit in the lower portion of the enclosure, a lower rotary shelf having a central opening for the passage of heated currents therethrough, an upper rotary shelf, and a tubular like member positioned in association with the opening in the lower shelf for directing heated currents substantially against the under side of the upper shelf, said tubular like member having an outwardly flared deflector at its upper end. 110

7. In a bake oven, walls defining an oven enclosure, a heat unit in the lower portion of the enclosure, a lower rotary shelf having a central opening for the passage of heated 120

125

130

currents therethrough, an upper rotary shelf, and a tubular like member positioned in association with the opening in the lower shelf for directing heated currents substantially against the under side of the upper shelf, said tubular like member having an outwardly flared deflector at its upper end, said upper shelf being substantially closed in its central zone with its edges spaced from said enclosure walls.

10 8. In a bake oven, walls defining an oven enclosure, a heat unit in the lower part of the enclosure, two rotary shelves positioned one above the other, and both above the heat unit, the lower shelf having a central opening therethrough, the upper shelf being substantially closed in its central zone but its edges spaced from said enclosure walls, whereby heat in currents passes through said opening 15 toward the upper shelf, and a protector partition positioned between the lower shelf and the heat unit.

9. In a bake oven, walls defining an oven enclosure, a heat unit in the lower part of 20 the enclosure, upper and lower rotary shelves for bake goods, the lower one having a central opening and the upper one with its edge spaced from the enclosure walls, a protector partition positioned below the lower shelf, 25 and means for directing heated air currents which pass through the central opening of the lower shelf into close proximity with the under side of the upper shelf.

10. In a bake oven, walls defining an oven 30 enclosure, a heat unit in the lower part of the enclosure, upper and lower rotary shelves for bake goods, the lower one having a central opening and the upper one with its edge spaced from the enclosure walls, a protector 35 partition positioned below the lower shelf, and means for directing heated air currents which pass through the central opening of the lower shelf into close proximity with the under side of the upper shelf, said means 40 comprising a conduit like member located in said opening of the lower shelf.

11. In a bake oven, walls defining an oven 45 enclosure, a heat unit in the lower part of the enclosure, upper and lower rotary shelves for 50 bake goods, the lower one having a central opening and the upper one with its edge spaced from the enclosure walls, a protector partition positioned below the lower shelf, and means for directing heated air currents 55 which pass through the central opening of the lower shelf into close proximity with the under side of the upper shelf, said means comprising a conduit like member located in said opening of the lower shelf, and having an 60 outwardly directed flange at its upper end which lies relatively close to the upper shelf.

In testimony whereof I affix my signature.
ROBERT BOLLING.
